UNITED STATES PATENT OFFICE.

GEORGE W. COPE, OF DETROIT, MICHIGAN, ASSIGNOR TO WALTER F. STIMPSON, OF DETROIT,
MICHIGAN.

DESIGN FOR A SCALE-FRAME.

No. 38,976.

Specification for Design.

Patented Dec. 31, 1907.

Application filed December 26, 1906. Serial No. 349,586. Term of patent 14 years.

To all whom it may concern:

Be it known that I, GEORGE W. COPE, a citizen of the United States of America, residing at Detroit, in the county of Wayne and State of Michigan, have invented a certain new, original, and ornamental Design for Scale-Frames, reference being had therein to the accompanying drawing, forming part thereof.

The figure is a perspective view of a scale frame showing my new design.

I claim:

The ornamental design for a scale frame, as shown.

GEORGE W. COPE.

Witnesses:

AMELIA WILLIAMS,
JAMES P. BARRY.
